UNITED STATES PATENT OFFICE.

MAGNUS E. WIDELL, OF MAYWOOD, ILLINOIS, ASSIGNOR TO AMERICAN CAN COMPANY, OF NEW YORK, N. Y., A CORPORATION OF NEW JERSEY.

ADJUSTABLE AIR CUSHION FOR DRAWING DIES.

Application filed May 7, 1920. Serial No. 379,473.

To all whom it may concern:

Be it known that I, MAGNUS E. WIDELL, a citizen of the United States, residing in Maywood, in the county of Cook and State 5 of Illinois, have invented a new and useful Improvement in Adjustable Air Cushions for Drawing Dies, of which the following is a specification.

This invention relates in general to the 10 art of drawing sheet metal articles and has for its object broadly the provision of means for controlling the action of the cushion against which the drawing is performed, i. e., the control of the pressure on 15 the metal being operated upon in the drawing operation.

The invention contemplates the provision 20 of an air or other gas cushion for supporting the lower drawing die in a die press in such manner and under such control that the pressure of the air cushion may be accurately and positively controlled either at a constant pressure or with an increase of pressure on such occasions as may be necessary 25 or desirable.

Another important object of the invention 30 is the provision of accurate control for air pressure cushions in drawing apparatus and which once set in proper adjustment for the operation upon certain articles may be depended upon to maintain such adjustment and setting without constant attention of 35 the press operator.

Numerous other and important objects of 40 the invention will be apparent from the following description, which considered in connection with the accompanying drawings illustrates a preferred embodiment thereof.

The single figure shown on the drawing is 45 a transverse vertical section through the dies and fluid pressure providing means in which my present invention is embodied for the purposes of illustration.

Upon the drawing is shown a part of a 50 press bolster 1 supporting a drawing die assembly comprising a base 2 and carrying a fixed body member 3 and a movable die 4. The movable die 4 is adapted to co-operate with an upper die 5 when the latter is forced down to perform the drawing operation. Apertures 6 in the present instance are provided to receive pins 7 supporting the die 4 and fixed at their lower ends in a pin plate or disk 8. So much of the construction as has just been described is old

and well known in the art and further explanation of it is not believed necessary or desirable. A cylinder 9 is positioned beneath the bolster with its upper open end disposed about the pin plate 8 and this pin plate is mounted upon a plunger 11 within 60 the cylinder.

The cylinder is provided at the bottom with a cylinder head 12 having a large 65 threaded opening 13 at its center. Within this opening is mounted a hollow sleeve 14 forming the stem of a removable bottom 15 located within the cylinder and adapted to be raised and lowered by rotation of it, the threads on the sleeve and head being inter- 70 engaged to this end. A hollow plug or tube 16 extends through the sleeve 14 in threaded engagement therewith as indicated at 17. The tube or plug 16 has a chamber 18 at its 75 top in which is slidably mounted the stem 19 of the plunger 11. This stem 19 has an internal bore 21 extending throughout a part of its length, opening into the chamber 18 at the bottom, and having outlet ports 22 at the top of the bore and well beneath the 80 upper end of the stem. The tube or plug 16 has a bore 23 in communication with a pipe 24 through a fitting 25 embracing the end of the stem and communicating with the bore by an internal passageway 26 through 85 the fitting and a lateral pass 27 in the member 16.

As the dies descend the stem of the plunger is forced down within the plug 16 and this action occurs against air under 90 pressure admitted from the pipe 24 which may be considered a part of a fluid pressure source. The descent of the dies is accomplished against substantially a constant pressure until the ports 22 pass into the 95 chamber 18, the upper end of the plug acting as a valve to shut off communication between the air pressure source and the space within the cylinder and beneath the piston or plunger. This cutting off of the 100 communication results in the trapping of air within the cylinder and resulting compression upon further descent of the die, which compression of course increases the pressure 105 of the air cushion.

By reason of the threaded connections between the parts 12, 14 and 16 this shutting off of communication between the pressure source and the cylinder can be accomplished at any point in the drawing action and the 110

amount of resulting pressure, or in other words the ratio between the pressure at the source and the final pressure, may be altered and controlled at will. The increasing of 5 the pressure toward the end of the drawing action is of particular value in the making of deep draws.

When the pressure in the cylinder is normal, i. e. when the space beneath the plunger 10 is in communication with the source, the dies are acting against substantially a constant pressure and if desired the apparatus may be arranged, as will be readily apparent, to permit this condition to prevail throughout 15 the entire drawing action.

In order that the parts 12, 14 and 16 may be maintained in adjusted relation, I provide lock nuts 28 and 29, respectively, upon the parts 14 and 16. The part 14 is given 20 suitable formation at 31 to permit it to be grasped by a wrench or other turning tool and the end 32 of the plug is similarly shaped. I provide a nut 33 and a washer 34 for holding the fitting 25 in place and 25 against leakage.

It is thought that the invention and many of its attendant advantages will be understood from the foregoing description, and it will be apparent that various changes may 30 be made in the form, construction and arrangement of the parts without departing from the spirit and scope of the invention or sacrificing all of its material advantages, the form hereinbefore described being 35 merely a preferred embodiment thereof.

I claim:

1. In a die press having dies for drawing metal articles, a descending die member and a yieldingly supported companion member, 40 said yielding support for said die member including means forming an air cushion beneath the die and provided with outlet ports which are closed by the movement of the die, and means operated by the die movement 45 for controlling the pressure of said cushion as the drawing action proceeds.

2. In a die press having dies for drawing metal articles, a descending die member and a yieldingly supported companion member, 50 said yielding support for said die member including means forming an air cushion beneath the die and provided with outlet ports which are closed by the movement of the die, and means operated by the die movement 55 permitting change of pressure in said cushion.

3. In a die press having dies for drawing metal articles, a descending die member and a yieldingly supported companion member, 60 said yielding support for said die member including means forming an air cushion beneath the die and provided with outlet ports which are closed by the movement of the die, and means operated by the die movement for 65 permitting controlled increased pressure in

said cushion as the drawing action progresses in predetermined amount.

4. In a die press having dies for drawing metal articles, a descending die member and a yieldingly supported companion member, 70 said yielding support for said die member including means forming an air cushion beneath the die, and means for providing substantially uniform pressure in said cushion throughout a part of the drawing stroke 75 and means operated by the die movement for providing a suddenly increased pressure at a different part of said stroke.

5. In a die press having dies for drawing metal articles, a descending die member and 80 a yieldingly supported companion member, said yielding support for said die member including means forming an air cushion beneath the die, and means for maintaining first a constant and then, by the die movement, a suddenly increased pressure in said cushion during the drawing action and for varying the ratio between said constant and increased pressures.

6. In a die press having dies for drawing metal articles, a descending die member and a yieldingly supported companion member, said yielding support for said die member including means forming an air cushion beneath the die, and means for maintaining 95 first a constant and subsequently, and automatically by the die movement, a suddenly increased pressure in said cushion during the drawing action and adjustable to vary the duration of the constant pressure period. 100

7. In a die press having dies for drawing metal articles, the combination of drawing dies, a cylinder, a plunger in the cylinder and rigidly supporting one of said dies, a source of air under pressure communicating 105 with the cylinder beneath the plunger, and an air shut-off operable by the plunger at a predetermined point in the drawing action.

8. In a die press having dies for drawing metal articles, the combination of drawing dies, a cylinder, a plunger in the cylinder and rigidly supporting one of said dies, a source of air under pressure communicating with the cylinder beneath the plunger, and an air shut-off operable by the plunger 110 at a predetermined and adjustable point in the drawing action. 115

9. In a die press having dies for drawing metal articles, the combination of drawing dies, a cylinder provided with air escape 120 ports which are closed by the die movement, a plunger in said cylinder and rigidly supporting one of said drawing dies, a source of air under pressure communicating with the cylinder beneath the plunger, and an adjustable bottom in said cylinder for varying 125 the size of the fluid cushion irrespective of the die movement.

10. In a die press having dies for drawing metal articles, the combination of drawing 130

dies, a cylinder provided with air escape ports which are closed by the die movement, a plunger in the cylinder and supporting one of the drawing dies, a source of air under pressure communicating with the cylinder beneath the plunger, said communication being through the plunger stem, and means for cutting off said communication by the die movement.

10 11. In a die press having dies for drawing metal articles, the combination of drawing dies, a cylinder, a plunger in the cylinder and supporting one of the drawing dies, a source of air under pressure communicating with the cylinder beneath the plunger, said communication being through the plunger stem, and an adjustable sleeve embracing

said stem and for shutting off communication between said fluid pressure source and the space beneath the plunger.

12. In a die press for the drawing of metal, the combination of two die members, means whereby said members have relative movement for the drawing operation, fluid pressure means against which one of the die members is yieldable in said drawing operation, and cut-off means operated by said die movement at a desired stage of the drawing operation for cutting off said fluid pressure means from the source of such pressure, whereby the further drawing movement proceeds against a highly and automatically increased fluid pressure resistance.

MAGNUS E. WIDELL.
